(57) **CLAIM**

The ornamental design for a LED combination bow light, as shown and described.

DESCRIPTION

FIG. 1 is a rear elevation view thereof;

FIG. 2 is a front elevation view thereof;

FIG. 3 is a left side view thereof, with the ends of the wire broken away to indicate indeterminate length;

FIG. 4 is a right side view thereof;

FIG. 5 is a top plan view thereof;

FIG. 6 is a bottom plan view thereof; and,

FIG. 7 is a perspective view of a LED combination bow light showing my new design.
